UNITED STATES PATENT OFFICE

ROSTON TUCK, OF NEEDLES, CALIFORNIA

SAND-DRYING APPARATUS

Application filed March 17, 1930. Serial No. 436,326.

My invention relates to an apparatus for automatically delivering the wet or undried sand into the drying portions of the apparatus from whence the dried sand will pass into the delivery end of the apparatus and be conveyed into a sand screening portion and the graded sand and separated portions automatically delivered to separate containers or in separate lots for use.

10 My invention has for its object the provision of an apparatus whereby larger quantities of sand can be handled with less labor and with a more economical use of a drying medium or steam than has heretofore been 15 the case.

My improved apparatus is especially designed for use in the handling and drying of sand and removing foreign matter therefrom, so as to provide a clean sand of uniform size 20 of quality adapted for locomotive use and the like.

The objects and advantages of my invention will all be readily comprehended from the detailed description of the accompanying 25 drawings, wherein:

Figure 1 is a side elevation of my improved sand dryer, with a portion of a sand receiving container shown in section.

Figure 2 is a cross-sectional detail of the 30 sand screener.

Figure 3 is a top plan view of the apparatus.

Figure 4 is a detail view, partially in section, of a shock absorbing device.

35 Figure 5 is a sectional elevation of the sand elevating portion.

Figure 6 is a vertical sectional view of the sand drying hoppers.

Figure 7 is a top view of the sand drying 40 hoppers.

Figure 8 is a cross-sectional view taken substantially on the line 8—8 of Figure 7, as viewed by the arrows.

The specific embodiment of the invention 45 as disclosed in the drawings, involves a rectangular frame consisting of suitable upright members 15 preferably in the nature of angle bars, with cross-members 16 and brace bars as at 17 and 18; the uprights 15 support the sand receiving and drying hop-

per 19 at a sufficient height above the floor to permit the sand to move by gravity to any suitable depository lower than the floor-line.

The hopper 19 is preferably divided into a pair of compartments as shown in Figures 55 6 and 7, each compartment consisting of the end walls 20, 20 of the hopper, the side walls 21, 21 and the inner side walls 22, 22.

All of the walls are arranged at an inclination so as to converge toward the bottoms of 60 the compartments, as shown in Figures 6 and 7.

The walls of the hopper compartments, preferably for about two-thirds of the distance from the bottoms, are provided with a 65 plurality of holes, as shown at 23, of predetermined size and distances apart; as for example, holes three-fourths of an inch in size and approximately two inches between centers and covering the entire lower surface 70 of the hopper. The upper parts of the side walls are left imperforate, as shown more clearly in Figures 6 and 8, in order that the wet sand entering at the top of the hopper compartments is made to travel in the heating or drying zone before it is permitted to 75 gravitate or pass through the holes out of the drying zone.

Each hopper compartment is provided at 80 bottom with a perforated and hinged trap or drop door 24, as shown in Figure 6, which cover the entire bottoms of the hopper compartments.

The doors are suitably hinged, preferably 85 at the inner ends, to the intermediate walls 22, 22, and are held in closed position in any suitable manner. The doors are provided as a means of quickly cleaning out all sand and any foreign matter from the drying zone.

Each compartment of the hopper is provided with sand drying means comprising a skeleton type of top header 25 arranged adjacent the upper ends of the compartments, with portions in close proximity to the walls 95 of the compartment. The headers consist of suitable sized tubing coupled together at the ends into the rectangular formation of the compartment at top, as shown in Figures 6, 7 and 8. The end portions of the top 100

header are also each shown provided with couplings 26 for connecting the intermediate tubes 27, 27 which extend parallel with the longitudinal side portions, as shown in Figures 6 and 7. The bottom of each compartment is also provided with a skeleton type of header 28 of similar construction, but of smaller rectangular formation in keeping with the contour at the lower ends of the compartments resulting from the inwardly sloping side walls of the compartments. The bottom headers, like the top headers, are also provided with the intermediate tubes 29, 29, see Figure 6, extending from end to end and substantially parallel with the side portions. Extending downwardly from the various legs or portions of the top header to the corresponding legs or portions of the bottom header, including the intermediate portions or tubes of the headers, at uniformly spaced apart points, are a series of vertically disposed tubes 30 which connect the similar side portions of the headers and the similar intermediate tubes of the two headers.

This provides a drying zone extending throughout the entire depth of the hopper compartments. The drying zone, as is apparent from the structure shown, is also carried through the central mass of sand so that practically all portions of the incoming sand will be brought into contact or close relation with the heated tubes. The number of tubes employed are, of course, in keeping with the capacity of the hopper compartment.

During operation, steam, from a suitable source of steam supply under pressure is introduced by means of the valve control inlet, shown at 31, into the top headers from whence it passes downwardly through the vertically arranged tubes 30 and into the bottom horizontally disposed header 28 which latter, at a suitable point, is provided with a suitable discharge valved outlet, which may either discharge into a suitable condenser or allowed to waste.

Secured to the supporting frame member 15, about the bottoms of the drying compartments, is a sheet metal hopper or pan 32 of funnel shape, as shown in Figure 1. The funnel pan extends throughout the width and length of the apparatus and somewhat beyond the bottom sides of the compartments so as to catch all sand percolating or dropping through the holes 23 in the drying compartments; the walls of the pan being made with a sufficient downward pitch to direct or cause the sand to move to a common center, where the funnel pan or hopper 32 is provided with an opening which is provided with a suitable slide door or valve, indicated generally at 33 in Figure 1, for the purpose of controlling the amount or flow of sand from the funnel pan to a rotating sand screen 34.

The sand screen 34 has one end located directly beneath the discharge opening of the funnel pan. The upper end of the funnel pan, about the sides of the apparatus, is provided with an apron of light sheet metal, as shown at 35, to guide the sand discharging from the drying hoppers into the pan therebeneath; the apron being arranged parallel to the sides of the drier proper and at a suitable distance therefrom.

The sand screen 34 is preferably cylindrical in shape and of suitable mesh to screen or grade the sand to the desired size. The sand screen 34 is arranged at a suitable inclination, sloping downwardly toward the delivery end from which the coarser grains and any foreign matter may be discharged into a suitable receptacle or container. The screen 34 has a journal disposed centrally therethrough; the screen being provided at suitable points interiorly with the spider bearing, as shown at 36 in Figure 2, so as to cause the screen to rotate with its journal which latter is rotatably secured at its ends in any suitable bearing brackets, as at 37 and at 38 in Figure 1.

The screen may be rotated by any suitable motive power (not shown) and at a predetermined speed.

Mounted beneath the rotating screen and adjacent thereto and disposed throughout the length of the screen, is a sheet metal funnel member 39 terminating at its lower end in the downwardly disposed discharge tube or spout 40 which may lead into a suitable receptacle or container, as at 41, located beneath the floor on which the sand drying apparatus is located.

This sheet metal funnel member or chute 39 is adapted to catch the screened sand coming from the screener 34 and conduct the graded sand into the container or receptacle 41 or to any suitable tank or sand lift or conveyor which may be located therebeneath.

Adjacent to one end of the apparatus is a pair of vertically disposed guide members 42, 42 which may be in the nature of angle bars suitably secured at the lower ends to the floor on which the apparatus is located and of height commensurate with the height of the main portion of the apparatus, namely so as to extend above the top of the sand drying apparatus proper, as shown in Figure 1. These members are spaced apart, as shown in Figure 3, so as to provide a vertically disposed slideway for the platform 43, whose opposite sides are provided with projecting portions adapted to straddle the slide rails 42. The platform 43 is secured on a piston indicated at 44 arranged in a suitable cylinder indicated at 45 beneath the floor of the apparatus. The piston is intended to be driven by some suitable pressure medium, such as steam or air; the cylinder and piston being of size or length to permit the piston to raise

the platform 43 slightly above the top of the main portion of the apparatus.

5 A sand-carrying hod or receptacle 46 is preferably pivotally secured to the platform so as to permit the receptacle 46 to tilt into sand dumping position, shown in Figure 5, when it reaches the upper end of its travel.

In the specific exemplification of the invention, the receptacle 46, of any suitable size 10 commensurate with the capacity of the main portion of the apparatus, is shown provided with three side walls while the end disposed toward the main portion of the apparatus is left open. The bottom of the receptacle at 15 opposite sides is shown provided with V-shaped plates or downwardly disposed extensions 47 pivoted at their lowermost points, at 48, to the platform, thus enabling an easy 20 tilting of the receptacle. What may be termed the inner or dumping end of the receptacle 46 is provided at opposite sides with rollers 49 which rest against and ride along 25 on the vertically disposed guide rails 50 shown secured to the frame members of the apparatus; the guide rails 50 extend toward the top of the apparatus, where they bend inwardly over the top of the drying chambers, as shown at 51 in Figures 1 and 5, and thence 30 curved outwardly to receive the fastening or bracing portions 52 and 53 which latter are in 35 turn secured to the slideway members 42 and support the upper ends of the latter in place. By curving the upper ends 51 of the guide rails 50 and providing the brace member 52, as shown, a closed ended slot-way 54 is provided 40 for the rollers 49.

In operation, hod or receptacle 46 is held 45 in a horizontal position at the inner end by the rollers 49 which bear against rails 50; the rollers being such as to ride in the slotway 54, with the result that when the receptacle reaches a predetermined point in its upward 50 travel, namely where the rollers 49 reach the end of slotway 54, the receptacle 46 is forced 55 into a tilting position toward the main portion of the apparatus.

The sand, carried by the receptacle, is dumped into the drying chamber or chambers. In order to maintain the receptacle 46 50 in horizontal position, the outer side of the platform 43 is provided with one or a pair of supporting members or rods 55 suitably secured to the platform, as for example by means of the clamp nuts 56 and the upper 55 end of the supporting rod or rods provided with a receptacle engaging head or disc 57 which may be adjustably secured on the rod in order that the receptacle 46, in conjunction with the bearing and guide rollers 49, will be 60 held in horizontal position.

In order to protect the hod or receptacle against shock during this upward tilting movement, I prefer to provide the slideway rails 42 at a point adjacent to the initial tilting movement, with shock absorbing means

shown in the nature of links arranged in straddling relation with each slideway rail 42, as shown at 58 in Figure 1; the specific construction being shown in Figure 4 as consisting of a pair of rods 59, 59 secured to the 70 block 60 which is riveted or otherwise properly secured to the slide-rails, as shown in Figure 1. The outer ends of the rods 59 are provided with suitable head portions 61 which may be threaded on the ends of the rods and held against rotative movement by clamp nuts 62; and these heads in turn each have one end of a suitable coil spring 63 secured thereto; while the other end of each spring 63 is in turn secured to heads or blocks 64 which are secured to the ends of the U-shape member 65.

The block 60 is secured to the outer sides of the slide rails 52 while the closed end or U-shaped member 65 is disposed on the inner faces of the slide-rails and therefore arranged in the path of extended ears or lugs 66 at opposite sides of the hod or receptacle 46. As a result, when the platform and receptacle 46 reach a predetermined point in the upward 80 travel, the lugs 66 of the receptacle will engage with the U-shaped members 65 and cause the springs 63 to be distended and thus prevent a sudden upward slapping movement of the receptacle; the upward travel of the piston driven platform and therefore the movement of the rollers 49 into the upper end of the slotways 54 will force the receptacle to move into a dumping position against the pulling actions of the springs 63.

In the operation, wet sand is loaded into the receptacle 46 and the motive power or medium is then admitted to the cylinder 45 causing the piston 44 to travel vertically thereby moving the loaded receptacle 46 toward the upper end of the slideway; the piston travel being such that the free end of the receptacle is forced upwardly beyond the horizontal plane of the closed end of the slotways 54, so that the sand will dump into the drying chamber or chambers, see Figure 5. In the present exemplification of the invention, the apparatus is shown provided with a pair of drying chambers so arranged relative to the hoisting receptacle 46 that substantially equal amounts of the sand will be thrown into both chambers.

It will be understood that the heating medium, for example steam, has previously been admitted into the upper piping or headers 25, causing the steam to pass into all of the vertically disposed tubes 30 and downwardly into the bottom piping or headers 28; the latter being provided with a suitable drain or outlet so that hot steam will continuously pass through all of the tubing while the apparatus is in operation. The wet sand will thus be forced to come into contact with and pass in comparatively small quantities between all of the tubing which is disposed throughout the

entire height of the chambers, with the result that quick drying of the sand will take place, while the arrangement of the heating tubes will in no way retard the passage of the sand. As the upper ends of the drying chamber walls are not perforated, the sand is forced to move for a predetermined period of time through the drying zone before it reaches the discharge openings or holes in the side walls of the chambers as well as in the bottom doors so that a thorough drying of the sand during its passage by gravity through the chamber or chambers takes place. The dried sand will, therefore, all percolate through the side walls and bottoms of the chambers and fall into the hopper or pan disposed about the bottoms of the chambers and automatically discharge through the opening at the lowermost point in the hopper or pan into one end of a power operated screen which is preferably of the cylindrical type and arranged at a downward inclination, as shown in Figure 1, so that screened sand may pass from the screen while foreign matter and ungraded sand may automatically discharge from the opposite or lower end of the screen onto a suitable platform or into a suitable container.

The graded or screened dry sand discharges into the funnel shaped member disposed about the lower side of the screen. The screened graded sand will be discharged by the chute member 39 into any suitable receptacle or at any preselected point beneath the floor on which the drying apparatus is located. The upper ends of the cylindrical screen and the funnel shaped member may be secured to the discharge end of the hopper or pan 32 in any suitable manner which will induce all of the discharging sand to enter the screen; and any suitable motive power or means may be employed for agitating or for rotating the screen 34 at the desired speed. The sand drying chambers or receptacles are preferably rectangular in shape, as shown, so as to permit a proper arrangement of the drying pipes in order that the latter may be arranged in comparatively close relation with each other to cause substantially all portions of the sand to come into more or less intimate relation with the heating pipes or tubes. The walls of the chamber or chambers are made of sheet metal, welded, riveted or otherwise properly secured together and arranged at a proper inclination to ensure proper gravitation of the sand. The bottoms of the chambers are preferably hinged or otherwise movably secured in place in order that a quick cleaning out of the chambers may take place, especially of foreign matter of size greater than the size of the perforations or holes; and in order that the chambers may be readily cleaned out or in other words to permit access thereto, I provide the same at va-

rious points adjacent to the bottom with small clean-out doors, as indicated at 67.

In order that proper inspection of the apparatus may be had, the supporting framework is also provided with a suitable ladder or stairway, as at 68, leading to a platform indicated at 69.

With my improved device, larger quantities of sand can be handled, dried and graded with less labor than has heretofore been the case, while at the same time greater economy in the use of steam as a drying medium is obtained than has been the case in devices of this general character as heretofore employed.

I have shown a practical embodiment of my invention which has been described in terms employed merely as terms of description and not as terms of limitation, as modifications are possible and may be made without, however, departing from the spirit of my invention.

What I claim is:

1. A sand drying apparatus comprising a hopper of predetermined height and dimensions having side walls converging toward the bottom, said walls at a distance below the top being provided with holes of predetermined size and at prearranged distances apart; a perforated bottom for said hopper; drying means arranged in the hopper so as to have substantially the same general configuration of the hopper and consisting of a plurality of vertically disposed tubes arranged adjacent to the side walls throughout the height thereof and vertically disposed tubes arranged at intermediate points of the hopper; top and bottom headers connected to all of said tubes whereby the drying medium may circulate throughout the headers and all of said tubes; one of said headers having a controllable inlet, while the other header has a controllable outlet; a vertically disposed slideway arranged at one end of the hopper; a hod or sand holding receptacle arranged in said slideway to travel vertically; a power driven member, arranged to travel in said slideway, to which the hod or receptacle is pivotally connected so as to tilt endwise; a guide-way disposed parallel with said slideway and terminating at top in a sloping portion disposed toward the top of the hopper; means intermediate of the hod or receptacle and the guideway whereby the hod will be tilted toward the hopper when the power driven member and the rod reach the upper end of the slideway and the sand thereby dumped into the hopper; a funnel shaped pan beneath the hopper arranged to receive the sand discharged through the perforated side walls and the bottom of the hopper, said pan having a central discharge opening in its bottom; a power driven cylindrical screen arranged at an inclination with its upper end adapted to receive the sand discharging from said pan and to deliver the non-screened mat-

ter at its lower end; and a sloping chute member arranged about the lower side of the screen adapted to receive the screened sand and to deliver the same at a predetermined point.

5 2. A sand drying apparatus comprising a vertically disposed receptacle having side walls converging toward the bottom and provided with holes of predetermined size and 10 at prearranged distances apart; a perforated movable bottom for said receptacle; a plurality of steam conveying tubes arranged vertically within the receptacle adjacent to the walls and in vertical rows at intermediate 15 points in the receptacle; top and bottom headers connected to all of said tubes; a funnel-shaped pan arranged beneath said receptacle and having a central discharge opening at bottom; a power driven screen located beneath said discharge opening; a screened sand receiving chute mounted beneath said screen and adapted to deliver the sand at a preselected point; a vertically movable power driven sand hoisting member arranged at one side of the apparatus; and 20 means whereby said member is automatically moved into sand dumping position when it reaches a predetermined point in its upward travel.

30 3. A sand drying apparatus comprising a vertically disposed hopper having converging walls and a movable bottom, the walls at a distance from the top and the bottom being provided with perforations of predetermined size and spacing; vertically disposed tubes arranged in rows adjacent to the walls and at intermediate points in the hopper; piping connected to the upper ends of all of said tubes and piping connected to the lower ends of all of said tubes whereby circulation of a hot medium through said tubes is permitted; a funnel shaped pan located beneath the hopper adapted to receive the sand discharging through the perforations and having a central discharge opening; a power driven cylindrical screen arranged at an inclination with its upper end adapted to receive the sand coming through the discharge opening in said pan, while the lower end of the screen 40 is adapted to discharge the residue; a sloping chute located beneath said screen adapted to convey the screened sand at a preselected point; a vertically arranged slideway adjacent to said hopper; a power driven elevating platform arranged at the bottom of the slideway; a sand holding receptacle pivotally mounted on said platform; and means arranged at the upper end of said slideway whereby said receptacle is automatically tilted and the sand dumped into said hopper.

45 4. A sand drying apparatus comprising a vertically arranged rectangular chamber open at top and having converging walls and provided with a bottom, the walls at a distance below the top and said bottom having

perforations of predetermined size and spacing; hot medium conveying tubes arranged in vertical rows adjacent to the side and end walls of the chamber and at intermediate points in the chamber; continuous piping 70 connected to the upper and to the lower ends of all of said tubes; means for introducing a heating medium into the piping at one end of the tubes; a discharge in the piping at the other end; a dished hopper beneath said chamber arranged to receive the sand discharged through the perforations in the walls and bottom of said chamber, said hopper having a discharge opening at bottom; a power actuated screen arranged to receive the sand from the hopper discharge opening and adapted to automatically discharge the residue; a chute arranged to receive the screened sand and to convey the same at a preselected point; a power operated sand 75 holding receptacle adapted to elevate sand to the top of said chamber; and means whereby said receptacle is moved into sand discharging position when it reaches the top of said chamber.

80 5. A sand drying apparatus comprising a vertically disposed chamber, open at top and having converging walls, the walls and bottoms of the chamber having perforations of predetermined size and spacing; vertically 90 disposed tubes arranged in spaced vertical rows in said chamber; skeleton headers connected with the upper and the lower ends of the tubes so as to permit a heating medium to flow throughout the tubes; a hopper having downwardly sloping sides arranged beneath the chamber and provided with a discharge opening at bottom; a power actuated screen arranged beneath said opening and arranged to discharge residue at the opposite end thereof; a chute arranged beneath the screen to catch the screened sand and discharge it at a preselected point; a wet sand elevating member arranged to travel vertically adjacent to the chamber; and means whereby said member is automatically moved into sand dumping position when the member reaches the top of the chamber.

95 6. A sand drying apparatus comprising a vertically disposed receptacle provided with converging walls whereby the receptacle is provided with a plurality of chambers; the walls at predetermined distances from the tops being provided with perforations of predetermined size and spacing; the chambers being provided with perforated bottoms; vertically arranged tubes in said chambers; common headers arranged at the upper arm at the lower ends of the tubes, the upper headers being provided with steam inlets while the lower headers have steam outlets; a hopper disposed about the lower ends of the chambers adapted to receive the dried sand issuing through the perforations and provided at bottom with an outlet; a 100 105 110 115 120 125 130

movable screen mounted beneath said outlet and adapted to discharge unscreened matter therefrom; a screened sand receiving element disposed beneath the screen and adapted to convey the screened sand at a preselected point; means for agitating said screen; wet sand carrying means adapted to convey the sand toward the tops of said chambers; means for operating said first mentioned means; and means arranged along the path of the conveying means whereby the latter is caused to deliver the wet sand into said chambers.

7. A sand drying apparatus comprising vertically disposed chambers provided with walls converging toward the bottom; the walls having perforations of predetermined size and spacing; perforated movable bottoms for the chambers; vertically disposed tubes in said chambers arranged in rows adjacent to the walls and in rows intermediate of the sides; a steam introducing pipe connected to the upper ends of all of the tubes in each chamber; a steam outlet pipe connected to the lower ends of all of the tubes in each chamber; a hopper with sloping sides arranged beneath the chambers and having an outlet; a sloping screen arranged to receive the sand from said outlet and adapted to automatically discharge the unscreened material at a prearranged point; a chute arranged beneath the screen to receive the screened sand and adapted to discharge the same at a preselected point; power means for actuating the screen; a wet sand hoisting receptacle adapted to travel toward the upper ends of the chambers; means whereby the wet sand is discharged into the chambers when the receptacle reaches a predetermined point in its travel; and power means for actuating said receptacle.

8. A sand drying apparatus comprising a vertically disposed chamber, the walls and bottom whereof have perforations of predetermined size and spacing; vertically disposed tubes arranged throughout said chamber; means common to all of said tubes and connected to the ends thereof for circulating a heating medium through said tubes; a dried sand receiving member arranged beneath said chamber and adapted to automatically discharge the sand at a common point; a movable screen arranged beneath said discharging point and adapted to automatically discharge unscreened material at a prearranged point; means for actuating said screen; means arranged to receive the screened sand coming from said screen and to discharge the same at a preselected point; wet sand carrying means adapted to convey the sand to the receiving end of the chamber and to automatically discharge the sand into the chamber; and means for actuating said wet sand conveying means.

CERTIFICATE OF CORRECTION.

Patent No. 1,781,484.

Granted November 11, 1930, to

ROSTON TUCK.

It is hereby certified that error appears in the printed specification of the above numbered patent requiring correction as follows: Page 5, line 124, claim 6, for the word "arm" read and; and that the said Letters Patent should be read with this correction therein that the same may conform to the record of the case in the Patent Office.

Signed and sealed this 6th day of January, A. D. 1931.
